US00D729241S

(12) **United States Design Patent**
Sogabe

(10) **Patent No.:** **US D729,241 S**
(45) **Date of Patent:** **** May 12, 2015**

(54) **ARITHMETIC AND CONTROL UNIT**(71) Applicant: **Sony Computer Entertainment Inc.**,
Tokyo (JP)(72) Inventor: **Takashi Sogabe**, Tokyo (JP)(73) Assignee: **Sony Computer Entertainment Inc.**,
Tokyo (JP)(***) Term: **14 Years**(21) Appl. No.: **29/421,915**(22) Filed: **Oct. 18, 2012**(30) **Foreign Application Priority Data**May 15, 2012 (JP) D2012-011278
(51) **LOC (10) Cl.** ..... **14-02**(52) **U.S. Cl.**USPC ..... **D14/356**; D21/324(58) **Field of Classification Search**CPC F21V 8/00; G02B 6/0001; G06F 1/16;
H05K 5/0026; H04N 5/50; H04N 5/64
USPC D13/158, 162, 162.1; D14/300, 314,
